AIR-CIRCULATING EQUIPMENT

Adiel Y. Dodge, South Bend, Ind.

Application November 8, 1934, Serial No. 752,042

13 Claims. (Cl. 261—28)

This invention relates to a system and equipment for circulating air, for example in conditioning the air in a dwelling, and preferably also for treating the air so circulated.

One object of the invention is to provide for such a system a compact and simplified unit which will (1) wash and humidify or dehumidify the air and (2) cool the air when desired, and (if desired) which may (3) ozonize or otherwise treat the air, at the same time circulating it through the system. Preferably this unit is designed to be used with heating equipment in a complete system which also embodies substantial novelty. Auxiliary refrigerating equipment may also be used in conjunction with the system if desired.

In the embodiments illustrated in the drawings, the air is circulated by a unit comprising blades which are sealed at their ends by water which is continuously introduced in jets or a spray or the like, and withdrawn from the unit, to provide a circulation of water which can be utilized to wash and humidify or dehumidify the air.

The above and other objects and features of the invention, including various novel combinations of parts and desirable particular constructions, will be apparent from the following description of the constructions and arrangements shown in the accompanying drawings, in which:

Figure 1 is a cross section through one form of air-circulating and treating unit;

Figure 2 is a section through the unit at right angles to Figure 1;

Figure 3 is a section corresponding to Figure 1, but showing a modified form of unit; and

Figure 4 is a diagram of a complete air-conditioning system utilizing the novel unit of Figure 1.

The novel unit illustrated in Figure 1 comprises a suitable housing 10 in which is rotatably mounted a rotor 12 provided with radial vanes 14 or the like protruding therefrom. Rotor 12 is also provided with suitable radial apertures or jets 16 communicating with a central port 18. In port 18 there is located a valve 20 which may be revolved into different effective positions.

In the summer time, when it is desired to cool and dehumidify the air, cold water is admitted into port 18 under pressure. Due to the pressure and centrifugal force the water is caused to pass through apertures 16 and spray therefrom radially. Due to the shape of the housing 10 this water is trapped and caused to swirl by the rotor 12 in substantially the form shown by dash lines

22. The water so swirling around creates empty spaces between the rotor blades, varying in size at different angular positions as shown, thus creating a form of pump. Air is admitted through a pipe 24, provided the rotor is turned in the direction indicated by arrow 26. Since the unit is symmetrical it may be turned in the opposite direction, in which case, the intake and outlet ports are reversed. Air is thus taken into the empty spaces which are increasing in volume, and after each vane 14 has passed the intake port 24a the volume of the spaces becomes smaller, thus compressing the air. During this process the cold water is being continuously sprayed into the spaces between the blades, through the apertures 16. When the rotor is turned a little less than one-half of a revolution further the spaces increase in size, thus allowing the air to expand until the vanes 14 approach the outlet port 26b where the spaces again diminish in volume, thus forcing the air out of the outlet pipe 26. It will be seen that the air is washed, cooled, and dehumidified while it is circulated as described.

In order to further condition the air I prefer to introduce suitable insulated electrodes 28 from which a high potential high frequency current may be caused to discharge, producing ozonization. The electrodes 28 may be made up like spark plugs with a somewhat larger spark gap. In order to maintain a desired pressure level, suitable water outlet ports 30 and 30a are introduced which communicate with a riser pipe 32 rising to a suitable head, thus determining the back pressure against which water is allowed to escape.

In Figure 2, valve 20 is more fully shown as is also the water intake pipe 40. Valve 20 may be revolved to different positions by means of a squared end 42 and locked in position by means of a jam nut 44. For example, in the winter time valve 20 may be revolved 180° and warm water admitted to cause humidification and heating and air washing instead of de-humidification and washing and cooling, as described for summer use, and in which case, the ozonizers may be re-located if desired. Shaft 46 may be driven by any suitable prime mover.

Figure 3 is very similar to Figure 1, merely showing a housing 61 somewhat different in shape from the housing 10.

Due to the compression of the air and future expansion a degree of cooling may be secured somewhat below that secured by the circulation of water at a given temperature without compression and expansion. I also wish to point out that by

allowing the air to expand in the illustrated manner, I recover some of the energy previously put into the compressed air as well as bring about the desired expansion. It is obvious that the discharged air system should operate at a pressure lower than the maximum compression pressure attained in my unit in order to benefit from this just mentioned recovery of energy. For the purpose of illustration, I might compress the air to four atmospheres at the smallest space and circulate the air at one and one-half atmospheres at the outlet pipe 26, in which case, I will have recovered the energy represented by two and one-half atmospheres of pressure.

Figure 4 is a diagram showing one form of complete system, in which there is included a hot air furnace 41, or other suitable air distribution chamber. A suitable intake pipe 43 takes air from the building in which air is to be conditioned and delivers it either to the chamber 41 direct or to a unit 45 of the type shown in Figures 1 and 2. An air intake opening is shown diagrammatically at 46, and an air outlet at 48. Air conduits 50, 52, and 54 lead from the furnace 41 to air outlets 48 appropriately located in the building. Dampers 56 of regulating valves control the amount of air discharged through the respective conduits in which the dampers 56 are located. A conduit 58 admits fresh air from outside doors. A suitable control means such as a damper 60 regulates the amount of fresh air admitted. A fire door 62 may be provided for chamber 41, where fuel may be fed in if 41 is to be used as a heating unit in the winter time, and a clean-outdoor 64 may be provided for removing ashes, for instance, if coal is used for fuel. A flue pipe is illustrated at 66, provided with a suitable damper. A pipe 65 short-circuits from pipe 43 to pipe 68 which is the intake pipe to chamber 41.

There is preferably an automatic counter-weighted damper or valve 70 in pipe 65 provided with an adjustable counter-weight 72. Should unit 45 be stopped in the winter time when 41 is being used as a heater, cold air entering through pipe 43 will open valve 70 causing counter-weight 72 to pass center, allowing valve 70 to remain open. However, should 45 be started, pressure caused in the discharge pipe 74 will cause damper 70 to close bringing the counter-weight back to the position shown, thus causing the damper 70 to remain closed until 45 is again stopped. 76 illustrates diagrammatically a suitable electric motor used as a prime mover for the unit 45. 45 and 76 are connected by a shaft 78.

As previously described, water is fed to the unit 45, pipe 80 illustrating a pipe from the city water supply. By opening a valve 82 and closing a valve 84 water is allowed to flow from 80 through 82 and through pipes 86, 88, 90 into the unit 45 as previously described. Water is discharged from the unit 45 through a pipe 92 into an elevated tank 94. The head elevation of the pipe 92 should be sufficient to produce the desired back pressure. Water from the tank 94 overflows into the sewer through a pipe 96.

This outlines the water circuit for summer use when cooling and dehumidification are desired. In the bottom of the chamber 41 is provided a suitable drip pan 98 to catch any condensed vapor and water. Water from the pan 98 is drained into the sewer through a pipe 100 after passing through a suitable trap 102. The trap 102, as diagrammatically illustrated, represents

a conventional water trap of sufficient extra head to withstand the air pressure in the chamber 41. However, the trap 102 may if preferred be a float controlled type trap. The trap 102 is provided to prevent loss of air from the chamber 41 when there is no condensation to be drained therefrom. In this arrangement, city water may be used as a heat absorbing medium in sufficient quantities to give the desired results, controlled by the valve 82 and allowed to drain into the sewer after use.

At 104 is illustrated diagrammatically a humidistat, for instance of the hair type. Electric contact points 106 and 108 are the usual electric front and back contact points. At 110 is illustrated a thermostat having front and back contact points 112 and 114. Each of the contact points 106, 108, 112, and 114 is provided with suitable adjustments illustrated at 116. While these contact points are shown as mechanical contact points, they may be of the mercury tube type, such as illustrated in my Patents Nos. 1,898,006 and 1,895,918. Contact point 114 when closed by the thermostat 110 controls the heating plant by means of any one of the several well-known methods in use. A wire 118 connects to the furnace control referred to. Switches 120, 122, and 124 are used to change the circuit from a winter circuit to a summer circuit. Wires 126 and 128 are main power lines from which a suitable wiring leads through a control relay 130 to the motor 76. A suitable transformer for energizing relay 130 is shown at 132. Switch 134 is a shunt switch by which the motor 76 may be energized, when desired, regardless of the relay 130. Food, etc., may be placed in the empty fire box and kept cool when the system is being used as a cooling system.

Coil 140 is a suitable water coil placed in the chamber 41 near the fire box for warming water to be used for washing air and humidifying air in the unit 45 in the winter time. Pipe 142 leads from the coil 140 to the tank 94. A suitable transmission connecting the motor 76 and the unit 45 is indicated at 150.

In operation during the summer, adjustment 116 for contact point 106 is so adjusted to cause an electric contact to take place if and when the humidity exceeds a certain predetermined degree. Likewise contact point 112 is set so that electric contact will be made when the temperature exceeds a certain predetermined degree. Switches 120 and 124 are closed and remain so during the summer months. Should electric contact be made at either point 112 or 106 relay 130 will be caused to close its electric circuit, thus starting the electric motor 76 and causing the unit 45 to operate as previously described. Unit 45 sucks air through the opening 46 and a small predetermined amount of fresh air through the pipe 58 according to the setting of valve 60. This air is carried through the unit 45 in the manner previously described and is discharged through pipes 74 and 68 into the chamber 41. From the chamber 41 it is distributed through the various pipes 50, 52 and 54 and into the various rooms of the building through discharge openings such as 48. As previously described, water is taken from the city supply, regulated in quantity at valve 82, through pipes 86, 88 and 90 into the unit 45. When the condition of high temperature or high humidity has been corrected, the electric circuit at both of the contact points 106 and 112 will be allowed

to open by their respective instruments 104 and 110, thus de-energizing the relay 130 and breaking the contacts which control the motor 76, allowing unit 45 to cease operation. If desired, 5 valve 82 may be augmented by an electrically controlled valve, diagrammatically illustrated at 144, to stop the flow of water when the motor stops.

In the winter time the switches 120 and 124 10 are opened and the switch 122 is closed, and contact points 114 and 108 are regulated to make electric contact at and beyond some predetermined points of humidity and temperature. When electric contact is made at 114 the heat 15 from the heating system is caused to increase by any of the well-known methods of increasing the fuel feed, etc. Should the air become too dry the humidistat 104 will allow electric contact to be made at point 108, thus exciting relay 130 20 and causing the relay to close the circuit which controls the motor 76 and causing the unit 45 to operate as previously described.

At the same time the switch 122 is manually closed, switches 120 and 124 are manually opened, 25 and valve 42 in Figure 2 is changed manually to the winter position. Also valve 84 should be opened and the valve 82 nearly closed, sufficient opening in the valve 82 being allowed to produce a flow to maintain the water supply in the 30 tank 94. With this arrangement the water circulates from tank 94 through pipe 142, valve 84, heating coil 140 and pipes 86, 88, and 90, due to the natural centrifugal pumping action 35 of the unit 45, and thus warm water is supplied to the unit 45 and discharged from it through pipes 92 back to the tank 94. An oversupply of water is allowed to overflow from tank 94 through pipe 96 into the sewer. In this way, 40 warm water is used over and over again for the purpose of air washing and humidification during the winter, only sufficient new water being admitted through the valve 82 to maintain the supply. If for any reason it is desirable to manually over-rule the instruments 104 and 110 45 this may be done by closing and opening the switch 134 manually.

While various constructions and arrangements have been described in detail, it is not my intention to limit the scope of my invention by that 50 description, or otherwise than by the terms of the appended claims.

I claim:

1. An air-conditioning system comprising a unit having means for taking in water in a spray and means cooperating with said water to compress air through which the water is sprayed, whereby to wash and change the temperature and humidity of said air, in combination with means for heating water supplied to said unit 55 and air discharged from said unit.

2. An air-conditioning system comprising a unit having means for taking in water in a spray and means cooperating with said water to compress air through which the water is sprayed, 60 whereby to wash and change the temperature and humidity of said air, in combination with a furnace arranged for heating water supplied to said unit and also air discharged from said unit, and means for distributing the heated air.

3. An air conditioning unit comprising a rotor 70 having radially-extending vanes and a central axial water intake and a plurality of radial jets from said intake arranged between said vanes, and adapted to spray water between said vanes, 75 and an inclosing casing for said rotor spaced from

the tips of said vanes throughout most of its circumference and approaching them closely at two points, said casing having a water outlet, and an air intake and an air outlet on opposite sides of each of said two points, whereby water circulated by said vanes seals the tips of said vanes and is held by centrifugal force against said casing to cooperate with said vanes in forming between the vanes air spaces which vary in size as the rotor turns angularly. 10

4. An air conditioning unit comprising a rotor having vanes and a water intake and jets from said intake arranged between said vanes and adapted to spray water between said vanes, and an inclosing casing for said rotor spaced from the 15 tips of said vanes throughout most of its circumference and approaching them closely at two points only, said casing having an air intake and an air outlet on opposite sides of each of said two points. 20

5. An air conditioning unit comprising a rotor having radially-extending vanes and a central axial water intake and a plurality of radial jets from said intake arranged between said vanes and adapted to spray water between said vanes, 25 and an inclosing casing for said rotor spaced from the tips of said vanes throughout most of its circumference and approaching them closely at two points, said casing having a water outlet and an air intake and an air outlet on opposite 30 sides of each of said two points, whereby water circulated by said vanes seals the tips of said vanes and is held by centrifugal force against said casing to cooperate with said vanes in forming between the vanes air spaces which vary in 35 size as the rotor turns angularly, said water intake being provided with a control valve adjustable to vary the angle at which water is discharged through said jets. 40

6. An air conditioning unit comprising a rotor having vanes and a water intake and jets from said intake arranged between said vanes and adapted to spray water between said vanes, and an inclosing casing for said rotor spaced from the 45 tips of said vanes throughout most of its circumference and approaching them closely at two points only, said casing having an air intake and an air outlet on opposite sides of each of said two points, said water intake being provided with a control valve adjustable to vary the angle at 50 which water is discharged through said jets. 55

7. An air conditioning unit comprising a rotor having radially-extending vanes and a central axial water intake and a plurality of radial jets from said intake arranged between said vanes and adapted to spray water between said vanes, 60 and an inclosing casing for said rotor spaced from the tips of said vanes throughout most of its circumference and approaching them closely at two points, said casing having a water outlet and an air intake and an air outlet on opposite sides of each of said two points, whereby water circulated by said vanes seals the tips of said vanes and is held by centrifugal force against said casing to cooperate with said vanes in forming between the vanes air spaces which vary in size as the rotor turns angularly, said water outlet having connected therewith means for maintaining a back pressure in said casing. 65

8. An air conditioning unit comprising a rotor 70 having radially-extending vanes and a central axial water intake and a plurality of radial jets from said intake arranged between said vanes, and adapted to spray water between said vanes, 75 and an inclosing casing for said rotor spaced 75

from the tips of said vanes throughout most of its circumference and approaching them closely at two points, said casing having a water outlet and an air intake and an air outlet on opposite sides of each of said two points, whereby water circulated by said vanes seals the tips of said vanes and is held by centrifugal force against said casing to cooperate with said vanes in forming between the vanes air spaces which vary in size as the rotor turns angularly, said water intake being provided with a control valve adjustable to vary the angle at which water is discharged through said jets, said water outlet having connected therewith means for maintaining a back pressure in said casing.

9. A pump comprising a vaned rotor and a casing therefor closely approaching the tips of the rotor vanes at two points only and having intake and outlet openings on opposite sides of each of said two points, and which has means for introducing a sealing liquid through said rotor.

10. A pump comprising a vaned rotor and a casing therefor closely approaching the tips of the rotor vanes at two points only and having intake and outlet openings on opposite sides of each of said two points, and which has means for introducing a sealing liquid through said rotor and which has a liquid outlet provided with means for maintaining a back pressure in said casing.

11. An air conditioning compressor and expander comprising a non-circular casing, a vaned rotor in said casing closely approaching the casing at two points, and gas inlet and outlet ports in the casing on opposite sides of each of said two

points whereby gas admitted through said inlet port will be compressed and then expanded before being discharged through said outlet port whereby at least a part of the energy absorbed by the gas during compression will be returned to the rotor thereby during expansion and means to cool the compressed gas prior to its expansion.

12. An air conditioning compressor and expander comprising a casing having a plurality of enlarged lobes joined by portions of less radius than the lobes, a vaned rotor in the casing spaced from the surfaces of the lobes and more closely approaching said portions, said casing adapted to contain liquid to seal the rotor vanes, an air inlet opening into one of the lobes and an air outlet opening into another lobe whereby air drawn into the inlet will be first compressed and then expanded before being discharged out of the outlet, and means for circulating liquid through the casing.

13. An air conditioning compressor and expander comprising a casing having a plurality of enlarged lobes joined by portions of less radius than the lobes, a vaned rotor in the casing spaced from the surfaces of the lobes and more closely approaching said portions, said casing adapted to contain liquid to seal the rotor vanes, an air inlet opening into one of the lobes and an air outlet opening into another lobe whereby air drawn into the inlet will be first compressed and then expanded before being discharged out of the outlet, means for supplying liquid axially of the rotor, and means for conducting liquid from the casing.

ADIEL Y. DODGE. 35
